(57) **CLAIM**

The ornamental design for a set of tennis courts, as shown and described.

DESCRIPTION

The file of this patent contains at least one drawing executed in color. Copies of this patent with color drawing(s) will be provided by the Office upon request and payment of the necessary fee.

The following is a description of a new, original and ornamental design for an set of tennis courts of which the following is a specification, reference being had to the accompanying sole drawing, which shows a perspective view of the set of tennis courts.

In the drawings, the broken lines depict environmental subject matter only and form no part of the claimed design.
